UNITED STATES PATENT OFFICE.

ALFRED W. A. FINCH, OF DETROIT, MICHIGAN, ASSIGNOR TO ROBERT FULTON AND BELL MAY FINCH, OF DETROIT, MICHIGAN.

PIN-TICKET-MARKING DEVICE.

SPECIFICATION forming part of Letters Patent No. 739,408, dated September 22, 1903.

Application filed November 21, 1902. Serial No. 132,216. (No model.)

To all whom it may concern:

Be it known that I, ALFRED W. A. FINCH, a citizen of the United States, residing at Detroit, in the county of Wayne and State of Michigan, have invented certain new and useful Improvements in Pin-Ticket-Marking Devices, of which the following is a specification.

My invention relates to appliances to be used for holding pin-tickets while they are being marked by pencil, pen, or the like with the cost and selling price or with any other designations, and has for its object to provide a means of securing said pin-tickets or like objects in a relatively flat position and so that they will be sufficiently stationary to facilitate marking with a pen or pencil and will not be disturbed by the operator in the process of marking.

My invention consists in features of construction and combination of parts hereinafter more particularly described and claimed.

In the annexed drawings, constituting a part of this specification, Figure 1 is a perspective view of my invention. Fig. 2 is a lateral sectional view of the same. Fig. 3 is a cross-section. Fig. 4 shows a modified form of my invention.

Similar letters refer to like parts throughout the several drawings.

A is the base or body portion of my device, and is made of wood, papier-mâché, straw-board, or similar material, and is preferably made of such width as to accommodate in each line one dozen pin-tickets of the most common or standard size. This board is made of any convenient length and is provided on its upper surface with narrow parallel grooves B of sufficient depth to receive the pin or wire-staple part of the pin ticket or tags E. On the two lateral edges of the board are the slots C, in which the flanges H of the hand-rest D move. This rest D is made of relatively thin sheet metal and consists of the top surface, the ends G, bent at approximate right angles to the top surface, and the inwardly-projecting flanges H. The ends G are of sufficient height so that the top surface D can pass freely over the top surface

of the board after it has been covered with 50 pin-tickets. The grooves B, if desired, may be somewhat widened where they terminate at the edges of the board to facilitate inserting at the ends of said grooves the ticket pins or staples, or said pins or staples may be inserted in the board from the top part of the 55 grooves.

A modification of my invention is shown in Fig. 4, wherein, as shown, the board A upon its top surface is provided with inclined surfaces running parallel across the board. Near the top line of these inclined surfaces are the grooves B, similar to the grooves shown in Fig. 1, made at right angles to the inclined surfaces. As shown in this figure, the lateral 65 edges of the board instead of being provided with the slots C may be rabbeted, thereby providing the shoulders C' to hold the flanges H. If desired, the hand-rest D may be dispensed with and the boards, either plain, as 70 shown in Fig. 1, or with the inclined surfaces, (represented in Fig. 4,) used alone.

In the operation of my invention the boards are filled with pin tickets or tags, preferably one dozen in each row, as the articles upon 75 which these tags are principally used are marked in dozen lots and are uniform in price for at least that number. After the entire board has been filled the operator moves the hand-rest upward along the slots C or shoulders C' until the upper line of the rest is below the top row of tags, which are now marked, and the rest moved downward below the next row, and so on, until the entire boardful have been marked. The grooves B are relatively 85 narrow, so that the pin-tags are quite firmly held in position.

It is obvious that the boards when filled may be marked without the use of the hand-rest D, in which form I desire to cover my 90 invention as well as in connection with the hand-rest.

Having thus fully described my invention, what I claim, and desire to secure by Letters Patent, is—

1. In a pin-ticket-marking device, the combination of a base of wood or similar material, of parallel grooves thereacross, of slots

in the lateral edges of said base, and a hand-rest movable in said slots, substantially as described.

2. In a pin-ticket-marking device, the combination of a rectangular board having a series of grooves in the top surface thereof, a hand-rest of sheet metal or equivalent substance, lying in a plane parallel to the top surface of the board and having its ends bent 10 at right angles to the top surface of said rest and then inwardly in the plane of said top surface, rabbeted shoulders on the lateral edge of the board to retain the inwardly-projecting flanges of the hand-rest, substantially 15 as and for the purpose described.

3. In a device of the class described, the combination of a base portion, the top surface of which is provided with a series of grooves for receiving the staple or pin part 20 of marking-tags, of a hand-rest movable over the top surface and the tags arranged thereon, substantially as described.

4. In a pin-ticket-marking device, the combination of a board of wood or equivalent substance, of narrow grooves in the surface of 25 said board, and the said grooves widened at

their extremities where they terminate at the edges of the board, substantially as and for the purpose described.

5. In a pin-ticket-marking device, the combination of a board, the top surface of which is provided with a series of inclined surfaces parallel to each other and running across said board, of grooves in said surfaces, of a hand-rest movable over the top of said board 35 and the tickets, arranged thereon, substantially as described.

6. In a pin-ticket-marking device, the combination of a base portion of wood or equivalent material, the top surface of said base 40 provided with inclined portions extending parallel to each other and across said base, of grooves extending into said inclined surfaces, substantially as and for the purpose set forth.

In testimony whereof I have signed my name to this specification in the presence of two subscribing witnesses.

ALFRED W. A. FINCH.
